UNITED STATES PATENT OFFICE.

CHARLES J. BORGESON, OF SYRACUSE, NEW YORK.

CENTERING-TOOL.

1,152,070.

Specification of Letters Patent. Patented Aug. 31, 1915.

Application filed August 6, 1914. Serial No. 855,490.

To all whom it may concern:

Be it known that I, CHARLES J. BORGESON, a citizen of the United States, residing at Syracuse, in the county of Onondaga and State of New York, have invented certain new and useful Improvements in Centering-Tools, of which the following is a specification.

The purpose of this tool is to rapidly and accurately center the shafts and other round pieces which have to be turned or ground. In the ordinary machine shop manner the machinist locates the center with a pair of dividers and sinks the holes with a center punch. This method is not only slow but it is inaccurate, and a larger amount of material has to be provided for on the outside of the shaft to have enough stock so that the piece will be turned as intended. This, of course, adds to the cost of material as well as the time and labor consumed in removing the additional stock. If the center is placed with the applicant's tool, a minimum amount of stock is necessary. The advantage of this device is the perfect centering of a shaft or round piece of metal, and saving of material and labor.

One embodiment of the present invention is illustrated in the accompanying drawings, in which:—

Figure 1 shows an elevation of the centering tool; Fig. 2, a longitudinal section along line 2—2 of Fig. 4; Fig. 3, a similar section along line 3—3 of Fig. 4; Fig. 4, a transverse section along line 4—4 of Fig. 2; Fig. 5, a top plan view of the centering cup; Fig. 6, a top plan view of a washer; Fig. 7, a top plan view of the cup securing ring; Fig. 8 is a view similar to Fig. 1 showing the drill pushed forward; Fig. 9 is an elevation of a drill press with the centering tool in position; Fig. 10, a section along line 10—10 of Fig. 9; Fig. 11 shows a drill positioning gage; Fig. 12, a longitudinal section of the drill lock. Fig. 13 shows in axial section a modified form of the tool and Fig. 14, an end view of Fig. 13 with the body portion removed.

The tool holder is provided with the usual tapered shank 19, which is securely fastened in the body 18 of the tool holder. An outer, cylindrical casing 20 of about twice the length of the body surrounds the latter with sufficient play to permit the one to slide on the other. Two L-shaped slots 24, situated diametrically opposite each other, are cut

through the wall of the casing 20, and serve as guides for corresponding studs 30, tapped into the body 18. With the parts in the position shown in Figs. 1, 2 and 3, the studs 60 abut against the upper end of the slots 24 under the action of springs 36, as described later, thereby locking the parts together after assembling. At the inner end of the short leg of the slots is formed a recess 27 65 into which the studs 30 drop on the pushing up and turning of the casing 20 on the body 18.

At the lower end of the casing 20 is revolubly attached the centering cup 22 with a 70 conical bore 41 contracting upward and terminating with a cylindrical opening 36', which I preferably provide with rifle grooves 37, this for the purpose of preventing chips from the drilling to bind. The 75 centering cup 22 is suspended on a ledge 38 provided at the lower end of the casing 20. An adjusting nut 25 of slightly smaller diameter than that of the casing is threaded on the upper end of the centering cup 22, 80 and between this nut and the ledge 38 is placed a washer 26. A small pin 23, driven into the cup 22, projects upward, in order to engage with one of a plurality of holes provided in the washer 26, so as to key the 85 washer and cup together. The nut 25 has a threaded hole for a locking screw 40, which, when screwed in, projects downward slightly less than the thickness of the washer 26, and is positioned so as to engage with 90 any one of the holes 39 in the washer 26. Another washer 21 is placed between the end of the casing and the flange of the centering cup 22, thus transmitting the axial pressure from the blank or bar 42 to be centered to 95 the casing 20, when the blank 42 has been placed between the centering cup 22 and the table cup 31. Both washers are made from some fairly soft material such as fiber, brass, babbitt or the like.

The utility of this arrangement with the double washers will be evident. Ordinarily the nut 25 is not drawn up tight, but only enough to permit the cup 22 to revolve freely on the casing 20. When a blank of hard 105 material is placed between the two cups 22 and 31, the cup will first revolve with the tool casing while light pressure is put on but will later remain stationary with the blank 42, on account of the "slip" between it 110 and the casing 20, while greater pressure is put on and the rest of the tool holder re-

volves. In case where no "slip" is provided between the casing and the cup, the conical surface of the latter, although hardened, might be abraded by the sharp edge of the blank 42. This is now avoided.

On the other hand, if a piece of soft material is going to be centered, the cup 22 might be permitted to revolve with the rest of the tool, as the edge of the still-standing blank 10 would not be able to injure the conical surface of the centering cup 22. In such a case, the nut 25 would be drawn up tight on the centering cup 22 and locked thereto by the screw 40 engaging a suitable hole in the 15 washer 26, which, in itself, as already described is locked to the cup 22. The ledge 38 will then be tightly gripped between the two washers 21, 26, thus permitting only a slight "slip," between the cup and the casing or 20 none whatever.

The shank 19, has a central bore for receiving the plunger or drill-lock 33, behind which a compression spring 35 is inserted, tending to push the plunger downward. 25 This plunger is provided with an inclined groove 43, forming a key way for the binding screw 29, which is threaded and countersunk in the body 18, so as not to protrude beyond its cylindrical surface when screwed in. The turned-down point of this binding screw 29 runs through the side of the shank 19 in order to be able to enter the groove 43, and hold the plunger from turning. The inclined bottom of this groove causes a wedging 30 between the plunger and the binding screw 29 so that the greater the pressure on the plunger, communicated from the drill 44, the harder will be the binding of the screw. The lower end of the plunger is formed to 35 engage with the end of a double ended drill 44 and is for that purpose provided with prongs 45, which are made to engage in the helical flutes of the drill. Through the co-operation of screw 29 and plunger 33, the centering drill 44 is consequently prevented 40 from turning in the tool holder. It will therefore be seen that this plunger acts not only as a drill lock, but also as a positive stop, preventing the drill from being pushed 45 up, when pressed against the work.

In the central bore of the body-piece 18, the cylindrical sleeve or drill carrier 32 fits snugly, its upper end having a recess, into which the end of the plunger 33 is 50 made to enter. The inner diameter of the sleeve coincides with that of the drill 44 in order to give support along the whole length of the drill, and the outer diameter of the drill is the same as the diameter of the cylindrical opening 36' in the cup 22. As the 55 length of the sleeve 32 is such that it will enter this hole 36' in advance of the drill point reaching the blank 42, any wobbling of the drill is prevented, it being perfectly 60 guided throughout its entire length, close

down to its working point during operation. This will therefore produce a perfect centering hole in the blank. The lower part of the central hole in the sleeve 32 is tapered downward, as at 46, so that all shavings and 70 drill chips may easily drop down and collect in the large chamber formed by the conical surface in the cup 22 and the top of the blank 42. In order to still more facilitate 75 the removal of the chips, transverse flushing holes 47 are made in the sleeve, so that any lubricant such as oil or soap-water that enters through the openings 48 in the casing 20, will pass through the holes 47 and the conical opening 46 and run down to the drill 80 point, as well as passing on the outside of the sleeve 32 and through grooves 37, collecting in the conical chamber in cup 22. No possibility of clogging does therefore 85 exist.

The sleeve 32 is held in place by means of a holding screw 28, which with its narrow end enters a corresponding hole in the sleeve 32. This holding screw is threaded and countersunk in the body 18 in the same 90 manner as screw 29. The end of binding screw 28 is long enough to reach through the wall of the sleeve for the purpose of clamping the drill 44 in position. This clamping need however, only be very slight, 95 in order to hold the drill in engagement with the plunger 33, which, as has already been described, locks the drill against turning in the tool holder.

The two screws 28 and 29 are preferably 100 situated with their center lines in the same axial plane of the tool holder, and a longitudinal slot 49 is provided in the casing 20 located so as to register with the screws 28 and 29, when the tool holder is compressed 105 as shown in Fig. 8, and the studs 30 engage the notches 27. The screws may then be reached from the outside and loosened by means of a screw driver, when the drill 110 needs re-setting.

Compression springs 36 are housed in suitable chambers 50 provided in the body 18. For protecting them against chips and dirt, their lower ends are inclosed in cylindrical tubes 34, which abut with their bottom ends against the upper surface of the cup retaining nut 25. The outer diameter of the tubes is the same as that of the chambers 50, into which they project sufficiently 115 to be well guided. The springs 36 are inserted under compression so that they always tend to hold the parts in the position indicated in Figs. 1, 2 and 3.

Ordinarily the sleeve 32 acts as a gage for determining the depth of the hole to be 125 drilled, as the end of the sleeve will abut against the face of the bar or blank to be centered and prevent the drill from penetrating deeper into it, even if the drill continues to rotate.

If for one reason or another, the depth of the drilled hole in some pieces were required to be lessened, without changing the position of the drill in the holder, I provide an extra depth gage forming a positive stop for the tool holder, consisting of a plunger 53 which has a groove 52 tapered similarly to the groove 43 in the drill lock 33. A set screw 51, threaded in the tool body 18 so as to be below the cylindrical surface of the tool body, engages in the groove 52, and by means of this screw, the axial position of the plunger might be changed. Both the plunger 53 and its spring 54, which tends to push the plunger down, are housed in a bore 55 provided to one side of the shank 19 in the body 18. By letting the end of plunger 53 project beyond the lower end surface of the tool body, the plunger will abut against centering cup 22 sooner than the sleeve 32 abuts against the work piece, thus shortening the stroke of the tool sleeve and lessening the depth of the hole to be drilled. Whenever it is desired to go back to the regular depth of the hole, all that needs to be done is to push up and turn the casing 20 on the body 18 until the stud 30 enters the recesses 27, then loosening the set screw 51 with a screw driver, which can enter through a corresponding opening in the casing, then to push back plunger 53 and re-set with the set screw 51.

Fig. 11 shows a drill-setting gage 55' with a recessed portion 56 corresponding in shape to the drill point. The use of this gage will be easily understood. After pushing the casing 20 up on the body 18 and turning it until locked by studs 30 in the notches 27, as already described, the holding screws 28 and 29, which now register with the slot 49, are loosened with consequence that spring 35 partially pushes out the drill lock 33 and the drill 44. If now the gage is held over the drill point and pushed up until its head strikes the end of the sleeve 32, and the holding screws are retightened, the drill point will protrude to exactly correspond with the recess in the gage and uniform holes may thereupon be drilled in a number of blanks, care being taken that the drilling is continued until the sleeve 32 abuts against the work piece.

In Fig. 9 the tool holder is shown in position on a drill press. A brake for the centering cup in the form of a fork 57 is here provided. The prongs 58 of the fork are shaped so as to embrace and tightly hold the centering cup 22 when it enters between them, thus preventing the rotation of the cup while engaging with the work piece or blank 42, although the rest of the tool holder rotates.

The modified form of the centering tool illustrated in Figs. 13 and 14 is intended to be used in connection with a chuck which

holds the work piece firmly. In that case the centering cup is not necessary. The lock 33 for the drill 44 and its spring 35 are all the same as described above, the drill lock having an inclined key way 43 engaging with a holding screw 29 which may be, as before, tapped in the body 60 of the tool, but preferably as here shown is tapped in the drill sleeve 61. The sleeve in this case, is a receptacle both for the lock with its spring and the drill 44. It differs further by being split longitudinally to form three grippers for the drill, no holding screw like 28 being required. It is also provided with a swell 66 near its outer end. This swell is conical and engages with a corresponding recess in the tool body 60, so that the sleeve will firmly grip the drill 44, on being drawn into the tool body 60, which is accomplished by means of the interengaging threads at 62 of the sleeve and the tool shank 63. The shank, which is revolvably mounted in the tool body 60, is retained therein by means of a washer 63' and screws 64. By turning the shank until the cone shaped swell 66 abuts against its recess in the tool body, it is obvious that all the parts will be firmly locked together. Similarly to the first embodiment of the invention, the sleeve 61 constitutes a depth gage, the end of the sleeve forming a positive stop when abutting against the work piece, thus governing the depth of the hole to be drilled. The end is also cup shaped as at 64' with the transverse holes 47 communicating with the conical recess for the purpose of flushing. The sleeve 61 and the tool body 60 are non-revolvably connected by means of groove and pin 61'.

I claim:—

1. A centering tool having a central member holding the drill, a casing slidably mounted relative to said member, a centering cup revolvably mounted on said casing at the drill end of the tool, said cup having a conical recess for receiving the work-piece, and a central opening, the wall of which constitutes a support for the drill during operation and washers between said cup and said casing, for increasing the friction, and means for taking up wear on the washers.

2. A centering tool having a central member holding the drill, a casing slidably mounted relatively to said member, a centering cup revolvably mounted on said casing at the drill end of the tool, said cup having a conical recess for receiving the work-piece, and a central opening, the wall of which constitutes a support for the drill during operation; said wall being provided with rifle grooves for loosening and removing drill chips.

3. A centering tool having a central member holding the drill, a casing slidably mounted relative to said member, a centering cup revolvably mounted within said cas-

ing at the drill end of the tool, said cup having a conical recess for receiving the work-piece, and a central opening, the wall of which constitutes a support for the drill during operation; and means for increasing friction between the cup and the casing, said means comprising washers and adjusting means therefor.

4. A centering tool having a central member holding the drill, a casing slidably mounted relative to said member, a centering cup revolvably mounted on said casing at the drill end of the tool, said cup having a conical recess for receiving the work-piece, and a central opening, the wall of which constitutes a support for the drill during operation; and means for increasing friction between the cup and the casing; said means comprising a ledge on said casing, a friction washer on either side of the ledge, one of said washers being loose and the other keyed to the cup.

5. A centering tool having a central member holding the drill, a casing slidably mounted relative to said member, a centering cup revolvably mounted on said casing at the drill end of the tool, said cup having a conical recess for receiving the work-piece, and a central opening, the wall of which constitutes a support for the drill during operation; and means for causing friction between the cup and the casing; said means comprising a ledge on said casing, a loose friction washer between said cup and the outer face of said ledge, a second friction washer keyed to said cup and engaging with the inner face of said ledge; said second washer being provided with a plurality of key holes, a nut threaded on said cup and engaging with said second washer, a locking member in said nut constructed to engage with any one of said key holes, whereby said nut may be adjusted either to permit free turning of the cup relative to said casing, or to lock cup and casing together by tightening said nut so as to set up considerable friction between said ledge and said washers.

6. A centering tool having a body member with an axial bore, a spring-actuated plunger in the bore tending to push the drill forward, and provided with a wedge-shaped key-way, deepening rearwardly, a binding screw threaded in said body member and adapted to engage in said key-way, whereby said plunger will be locked the firmer, the greater the pressure becomes on its forward end.

7. A centering tool having a body member with an axial bore, a spring-actuated plunger in the bore tending to push the drill forward, a binding screw threaded in said body member adapted to lock said plunger in said body member, the forward end of said plunger being constructed to

firmly grip the end of the drill, whereby said plunger in coöperation with said holding screw, will prevent the turning of the drill relative to said member.

8. A centering tool having a body member with an axial bore, a spring-actuated plunger in the bore tending to push the drill forward, a binding screw threaded in said body member adapted to lock said plunger in said body member, the forward end of said plunger being constructed to firmly grip the end of the drill, whereby said plunger in coöperation with said holding screw, will prevent the turning of the drill relative to said member, and means for holding the drill in engagement with said plunger.

9. A centering tool having a body member with an axial bore, a spring-actuated plunger in the bore tending to push the drill forward, a binding screw threaded in said body member adapted to lock said plunger in said body member, the forward end of said plunger being constructed to firmly grip the end of the drill, whereby said plunger in coöperation with said holding screw, will prevent the turning of the drill relative to said member, and means for holding the drill in engagement with said plunger; said means comprising a second binding screw threaded in said body member.

10. A centering tool having a body member with an axial bore, a spring-actuated plunger in the bore tending to push the drill forward, and provided with a wedge-shaped key way deepening rearwardly, a binding screw threaded in said body member and adapted to engage in said key way, whereby said plunger will be locked the firmer, the greater the pressure becomes on its forward end, the forward end of said plunger having prongs for engaging in flutes of the drill.

11. A centering tool having a body member with an axial bore, a spring-actuated plunger in the bore tending to push the drill forward, and provided with a wedge-shaped key way deepening rearwardly, a binding screw threaded in said body member and adapted to engage in said key way, whereby said plunger will be locked the firmer, the greater the pressure becomes on its forward end, the forward end of said plunger having prongs for engaging in flutes of the drill, and means for holding the drill in engagement with said plunger; said means comprising a second holding screw threaded in said body member.

12. A centering tool having a body member with an axial bore, a spring-actuated plunger in the bore tending to push the drill forward, a binding screw threaded in said body member adapted to lock said plunger in said body member, a sleeve in said bore forming a carrier for the drill, a

- second binding screw threaded in said body member and adapted to hold said sleeve and the drill in position; and means for keying the drill to said plunger so as to turn with it. 5 13. A centering tool having a body member with an axial bore, a spring-actuated plunger in the bore tending to push the drill forward, a binding screw threaded in said body member adapted to lock said plunger in said body member, a sleeve in said bore forming a carrier for the drill, a second binding screw threaded in said body member and adapted to hold said sleeve and the drill in position; and means for keying the drill to said plunger so as to turn with it; the nose of said sleeve having a tapered recess around the drill point and communicating therewith for flushing, and transverse openings for removing drill chips. 10 15 20 14. A centering tool having a body member with an axial bore, a spring-actuated plunger in the bore tending to push the drill forward, a binding screw threaded in said body member adapted to lock said plunger in said body member, a sleeve in said bore forming a carrier for the drill, a second binding screw threaded in said body member and adapted to hold said sleeve and the drill in position; and means for keying the drill to said plunger so as to turn with it; a centering cup slidably mounted on said body member, said cup having a central opening corresponding in diameter to the outside diameter of said sleeve and constructed to register with and guide said sleeve in advance of the drill point reaching the work-piece. 25 30 35 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945 950

a casing provided with a guideway and slidably mounted around said body member, a centering cup on said casing at its forward end, a stop in said body member engaging in said guideway in the casing and permitting limited axial movement between them; a plurality of coiled springs; said body member providing seats for the springs, a closed housing for each spring, being guided at one end by said seat and at the other end abutting against said cup; said guideway being L-shaped with its transverse leg forward and provided with a notch for said stop, in order to lock the tool in its compressed position and uncover said binding screws, after the turning of the casing on the body member.

20. A centering tool having a body member with an axial bore, a spring-actuated plunger in the bore tending to push the drill forward, a binding screw threaded in said body member adapted to lock said plunger in said body member, a sleeve in said bore forming a carrier for the drill, a second binding screw threaded in said body member and adapted to hold said sleeve and the drill in position; and means for keying the drill to said plunger so as to turn with it; a casing provided with a guideway and slidably mounted around said body member, a centering cup on said casing at its forward end, a stop in said body member engaging in said guideway in the casing and permitting limited axial movement between them; a plurality of coiled springs; said body member providing seats for the springs, a closed housing for each spring, being guided at one end by said seat and at the other end abutting against said cup; said guideway being L-shaped with its transverse leg forward and provided with a notch for said stop, in order to lock the tool in its compressed position, after the turning of the casing on the body member, said casing having a window for said binding screws, registering with them when the tool is in its compressed position.

21. A centering tool having a body member with an axial bore, a spring-actuated plunger in the bore tending to push the drill forward, a binding screw threaded in said body member adapted to lock said plunger in said body member, a sleeve in said bore forming a carrier for the drill, a second binding screw threaded in said body member and adapted to hold said sleeve and the drill in position; and means for keying the drill to said plunger so as to turn with it; a casing provided with a guideway and slidably mounted around said body member, a centering cup on said casing at its forward end, a stop in said body member engaging in said guideway in the casing and permitting limited axial movement between them; a positive stop governing the amount

of axial displacement between said cup and the drill.

22. A centering tool having a body member with an axial bore, a spring-actuated plunger in the bore tending to push the drill forward, a binding screw threaded in said body member adapted to lock said plunger in said body member, a sleeve in said bore forming a carrier for the drill, a second binding screw threaded in said body member and adapted to hold said sleeve and the drill in position; and means for keying the drill to said plunger so as to turn with it; a casing provided with a guideway and slidably mounted around said body member, a centering cup on said casing at its forward end, a stop in said body member engaging in said guideway in the casing and permitting limited axial movement between them, a positive stop governing the amount of axial displacement between said cup and the drill, said stop comprising a spring actuated piston carried in a suitable chamber provided in said body member, and a set screw in said body member for adjusting the projecting length of said piston beyond the forward surface of said body member and in the direction of said cup.

23. A centering tool having a body member with an axial bore, a spring-actuated plunger in the bore tending to push the drill forward, a binding screw threaded in said body member adapted to lock said plunger in said body member, a sleeve in said bore forming a carrier for the drill, a second binding screw threaded in said body member and adapted to hold said sleeve and the drill in position; and means for keying the drill to said plunger so as to turn with it; a casing provided with a guideway and slidably mounted around said body member, a centering cup on said casing at its forward end, a stop in said body member engaging in said guideway in the casing and permitting limited axial movement between them, a positive stop governing the amount of axial displacement between said cup and the drill, said stop comprising a spring actuated piston carried in a suitable chamber provided in said body member, and a set screw in said body member for adjusting the projecting length of said piston beyond the forward surface of said body member and in the direction of said cup; said guideway being L-shaped with its transverse leg forward and provided with a notch for said first stop, in order to lock the tool in its compressed position for resetting the drill after the turning of the sleeve on the body member; said casing having a window for said set screw situated to register therewith when the tool is in compressed locked position.

24. A centering tool having a central member holding the drill, a casing slidably

mounted relative to said member, a centering cup revolvably mounted on said casing at the drill end of the tool, said cup having a conical recess for receiving the work piece; a brake for said cup mounted independently of and in fixed position relative to said cup.

25. A centering tool having a central member holding the drill, a casing slidably mounted relative to said member, a centering cup revolvably mounted on said casing at the drill end of the tool, said cup having a conical recess for receiving the work piece; a brake for said cup mounted independently of and in fixed position relative to said cup, said brake comprising a fork having prongs constructed to embrace

said cup to hold it from revolving while the cup engages with the work piece.

26. A centering tool having a central member holding the drill, a casing slidably mounted relative to said member, a centering cup revolvably mounted on said casing at the drill end of the tool, friction increasing means between said cup and said casing, said cup having a conical recess for receiving the work piece; said recess forming a receptacle for drill chips.

The foregoing specification signed at Syracuse, N. Y. this 16th day of July, 1914. ^{so}
CHARLES J. BORGESON.

In presence of—

C. GRACE KENTNER,
ALEX. PALMER.

Copies of this patent may be obtained for five cents each, by addressing the "Commissioner of Patents, Washington, D. C."
